HIGHWAY MARKER

Donald D. Taylor, Duncannon, Pa., assignor to
Advance Engineering Corporation, Duncannon,
Pa., a corporation of Pennsylvania

Application April 29, 1935, Serial No. 18,902

16 Claims. (Cl. 94—1.5)

My invention relates to the marking of streets and highways with surface indicia for defining traffic lanes, pedestrian crossings and the like.

Heretofore, several expedients have been attempted for the general purposes with which the present invention is concerned. One of the first to be used and that which, to the present time, is most generally employed, consists in the painting of appropriate lines upon the road or street surface. Such lines have the great disadvantage of short life, due to the abrasive action of vehicle wheels rolling and dragging thereon, weathering, and to staining and obliteration by road tar and spent oil dropping from the engines and other lubricated parts of automobiles.

Because of this primary objection to the painted line as a highway marker, numerous devices have been offered as substitutes, such devices, for the most part, being in the nature of studs provided with pin-like securing portions which are driven or otherwise anchored in the body of the highway at appropriately spaced positions to give the appearance of a dotted or "broken" line. Such devices are expensive for the purpose, partially because, to remain lustrous, they must be fabricated of, or jacketed with, expensive corrosion-resisting metal such as Monel or stainless steel. In some instances, attempts have been made to "jewel" the exposed portions of otherwise non-lustrous studs with faceted pieces of glass which reflect light. The mounting of such jewel-like elements in studs of rugged character is similarly so expensive as to be almost prohibitive for the provision of a highway marker of general utility. Moreover, adequate anchorage of such stud-like road-marking devices, as a class, is extremely difficult and further increases the cost of the finished highway line to such an extent that, as has been stated, painted lines, despite their short life, continue to be the expedient most generally used.

Relatively recently, efforts have been made to employ a ribbon or strip of lustrous metal and to anchor the metallic strip by means of an adhesive such as asphaltum. While such a construction has great merit from the standpoint of enhanced visibility and facility and rapidity of installation, the difficulty of obtaining an adhesive bond of adequate tenacity, especially on concrete highways, is self-apparent. Such a construction suffers damage not only by reason of the scraping and plucking action of vehicle wheels in lateral skidding and braking, especially when the wheels carry chains, but also by reason of the ingress of water, oil and dirt beneath the strip. In concrete roadways, particularly, con-

siderable moisture reaches such a strip, or its adhesive backing, through capillary attraction due to inherent porosity of such roadway materials as concrete. Differential thermal expansion and contraction also effects a buckling of the strip during extremes of temperature, with the result that the strip may become so wrinkled as to periodically lift from the surface of the roadway. Under such conditions, dirt will enter between the strip and the underlying roadway surface at numerous points, destroying the adhesive bond and assuring easy tearing and separation of the strip by vehicle wheels.

Other methods have been attempted, such as edgewise flanging of such strips into U form and the imbedding of the flanges in the material of the roadway. While the anchorage thus afforded is highly satisfactory, such structures are limited, for all practical purposes, to installation in new roadways during their construction. Such strips also are extremely expensive because of the high-cost non-corrosive metals required, as well as the difficulty of drawing and shaping the strips. Moreover, the application of such a structure to "curves" (which, incidentally, are the most common locations requiring marking) is practically impossible, except where the strip is of preformed curved configuration. Fabrication of such flanged strips in sections having curvatures of varying intensity involves manufacturing and shipping expense which is substantially prohibitive. Glare resulting from reflection of sunlight and light from approaching vehicle headlights, as well as the hazard of skidding on such rolled metallic strips, are further complications which adversely affect their adoption.

With the foregoing prior art structures and attendant problems in mind, my invention has, for its purpose, several well-defined objects. The primary object of my invention is to provide a zone-defining road marker which is rugged and will successfully withstand the numerous stresses and strains to which such markers are inherently subject.

It is another object of my invention to provide a highway marker which may be installed at low cost.

It is an object of my invention to provide a highway marker which is not subject to fouling by road tar and spent automobile lubricant.

It is an object of my invention to provide a highway marker which, while so lustrous as to be clearly visible even in bad weather, has the characteristic of so diffusing light reflected from the

- headlamps of approaching vehicles as to offer no additional traffic hazard.
- It is an object of my invention to provide a low-cost traffic marker which, like the painted line, is formed in situ upon the road surface.
- It is an object of my invention to provide a traffic marker which may be installed upon existing highways with facility equal to installation upon new highways.
- 10 It is an object of my invention to provide a traffic marker which, when worn, as may occur after a long period of severe use, may be renewed, or built up, with facility equal to the renewal of the painted line.

- 15 It is an object of my invention to provide a traffic marker which, though low in cost of installation, is not subject to injury by corrosion.
- It is an object of my invention to provide a traffic marker which has a satisfactory coefficient 20 of friction, and which, therefore, will not materially increase the road hazard known as skidding.
- It is an object of my invention to provide a road marker which is inherently bonded to the highway surface and which requires no adhesive 25 binding.
- It is an object of my invention to provide a road marker which may be installed with such rapidity that no interference with the normal use of the highway is occasioned.
- 30 It is an object of my invention to provide a highway marker which may be installed with accurate uniformity and which will present a pleasing appearance to the eye.

- Further objects and objects relating to details 35 and economies of construction and use will definitely appear from the detailed description following. In one instance, I accomplish the objects of my invention by the means set forth in the following specification. My invention is clearly 40 defined in the appended claims. A structure constituting a preferred embodiment of my invention is illustrated in the accompanying drawing, in which:

Figure 1 is a perspective view of a section of 45 highway provided with a central longitudinal highway marker constituting a preferred embodiment of my invention;

Fig. 2 is a cross-sectional view of a portion of 50 concrete highway provided with a highway marker of the form illustrated in Fig. 1;

Fig. 3 is a diagrammatic view of a portion of 55 apparatus employed for the installation of a highway marker of the type illustrated in Figs. 1 and 2, portions of said apparatus, as well as of the highway and marker, being shown in cross-section; and

Fig. 4 is a diagrammatic view of a preferred 60 form of apparatus for forming the highway marker illustrated in Figs. 1 and 2.

65 Similar reference numerals refer to similar parts throughout the several views.

In general, my invention consists in the provision of a narrow, band-like highway marker consisting of a narrow, tape-like, lustrous, corrosion-resistant strip of metal formed upon the surface of the highway and mechanically bonded directly thereto by casting thereon in situ.

More particularly, and with reference to the 70 accompanying drawing, in which I have illustrated a preferred embodiment of my invention, there is shown a cast strip 10 of zinc of elliptical cross-section embedded, inlay fashion, in a complementary trough or channel 11, formed in the surface of a conventional highway 12. Preferably, though not by way of limitation, my inven-

tion has particular application to monolithic highways such as are conventionally formed of concrete and provided with periodic expansion joints or gaps 13 suitably filled with resilient or compressible material 14. In employing the term "casting", particular reference is made to that method of casting which is effected by the spraying of molten metal in atomized form, and in which the atomized particles are in an unstable physical condition characterized by temporary plasticity such that solidification occurs at, or directly after, the moment of their deposit upon the surface being sprayed.

This general method of casting by atomization and projection of molten metal is well-known and, 15 for an understanding thereof, reference is made to the patent of Donald D. Taylor, No. 1,934,891, granted November 14, 1933, which patent discloses an apparatus of the general type adapted for the production of metal coatings generally. 20 In Figs. 3 and 4, there is diagrammatically illustrated apparatus including several metal-spraying nozzles 15 of the general type illustrated in the Taylor patent aforesaid, assembled in staggered relation. About the nozzles 15 is mounted 25 a shield 16 consisting of side plates 17 and 18 inclined toward their lower edges to constitute a mask held in slightly spaced relation with respect to the roadway surface by a suitable carriage (not shown). The carriage also supports 30 one or more sand-blasting nozzles 19, which are directed to discharge sand upon a narrow, band-like portion of the highway, directly in advance of the metal-spraying nozzles 15. The sand-blasting nozzles are also preferably so inclined 35 with respect to the band-like portion of the roadway surface as to not only clean the same of foreign matter, but also to provide a myriad of minute pits for a purpose later to be described. The shield member 16 of the apparatus, in addition to the side plates 17 and 18, is provided with a forward plate 20, the lower edge of which is similarly maintained in close proximity to the roadway surface. Mounted upon the plate 20, and disposed intermediate said plate and the 40 sand-blasting nozzles 19, is an air jet 21 arranged to discharge a broad jet of compressed air directly forward of the plate 20 to constitute an air curtain as well as a cleaner for removing such loose particles of sand as remain upon the band-like, pitted surface of the roadway prior to the spraying thereof with plastic metal discharged from the jets 15. Following the jets 15 in close proximity thereto, is a rotary wire brush 22 journaled in the carriage (not shown) which supports 45 the jets 15 and the shield 16.

More specifically, it will be noted that the staggered metal-spraying nozzles 15 are inclined with respect to the vertical and are so directed upon the sand-blasted portion of the highway 60 surface as to deposit the densest portion of their respective streams of atomized metal along the median zone thereof and thus build up a "crowned" strip having a maximum thickness along its central portion. Moreover, the projection of metal upon the pitted, band-like surface at an angle, and from two sides, insures an interlocking of the strip as formed, with the myriad of pits and projections in the roadway surface. As a result, the metallic strip becomes, 65 in effect, an integral portion of the highway, such that dislodgment therefrom, even under the most severe stresses, is a practical impossibility.

A metal strip, cast in the manner described, has the characteristic of being rather crystalline in 70 75

structure, as distinguished from a strip of metal which has been rolled or drawn. As a result, the appearance of the lustrous surface thereof, even when worn, is satin-like or slightly rough, 5 rather than brilliant and dazzling. This is an important feature because light reflected therefrom is of a diffused nature substantially free from glare. Similarly, I have found that the crown form of strip illustrated has less tendency 10 to induce glare, even when polished by the action of smooth traffic, because light is reflected therefrom in diverging rays.

Of a number of metals tested as material for a cast strip of the type described, zinc and aluminum have been found highly satisfactory. These 15 metals are relatively easy to spray, having low melting points and requiring low fuel consumption. They are amply light-reflective for the purpose, inexpensive, corrosion-resistant, and have good wearing properties.

Under some conditions, and in employing metals which take a high polish under the action of light traffic, it has been found desirable to diagonally striate the strip after formation. For 20 this purpose, the wire brush 22 is employed, which brush is diagonally journaled upon the supporting carriage and driven by a motor (not shown) at a moderate speed. Preferably, such striations 25 are formed transverse the strip 10 at an angle such that they are substantially perpendicular to light rays forwardly and downwardly projected from approaching vehicle lamps. These 30 striations tend to break up or diffuse light otherwise reflected to the eyes of drivers traveling in the opposite direction.

With an apparatus of the type heretofore described, the rate at which the strip 10 may be installed is limited and determined solely by the desired thickness of the strip.

The strip illustrated in Figs. 1 and 2 is of 40 elliptical cross-section and great thickness. For most purposes, a strip of far less thickness will suffice. Where a strip having a thickness of as little as .010 of an inch is employed, it is unnecessary to countersink the same as shown, although a cleaning and roughening of the highway 45 surface is essential to obtain adequate anchorage of the strip. With such interlocking of strip and roadway proper, differential thermal expansion 50 and contraction has been found not to effect localized buckling or breakage of the strip, apparently because the stresses are uniformly distributed for the full length of the strip section. Preferably, where the strip is applied to concrete 55 highways, it should be interrupted at the conventional expansion gaps or joints, as shown.

I am aware that the embodiment of my invention herein illustrated and described is susceptible of considerable modification without departure from the broad concept thereof. While zinc and aluminum have been found admirably well suited for the purpose of the present invention, other metals, pure or alloyed, may be employed. Similarly, changes in the size and form of the 60 strip are optional expedients. Likewise, though illustrated as a two-lane dividing traffic marker, it is equally applicable to definition of cross-walks in municipal areas. These and other variations will readily appear to those familiar with the objects and teachings of the present invention. I therefore claim my invention broadly, as indicated by the appended claims.

What I claim is:

1. A roadway having a roughened, narrow, 65 band-like surface formed therein, and a narrow

metallic strip coextensive with said band-like surface, in direct contact with said band-like surface and integrally mechanically bonded thereto in interlocking relation therewith by casting.

2. A roadway having a roughened, narrow, 5 band-like surface formed therein, and a narrow metallic strip coextensive with said band-like surface, in direct contact with said band-like surface and integrally mechanically bonded thereto in interlocking relation therewith by 10 fusion.

3. A roadway having a shallow, band-like trough formed therein, the walls of which trough are roughened, and a narrow metallic inlay of strip form set in said trough, in direct contact 15 with the walls thereof and mechanically interlocked therewith by fusion.

4. A concrete roadway having a narrow, band-like, pitted surface formed thereon, and a narrow metallic strip coextensive with said band-like surface, said metallic strip having its lower 20 face of a form complementary to said pitted surface and interlocked therewith by casting of said strip in situ upon said pitted concrete surface.

5. A roadway having lateral convexity or "crown", the apex of said crown being provided with a narrow, band-like surface of roughened character coaxial with said road, and a narrow metallic strip coextensive with said band-like 30 surface, said strip being complementarily roughened on its under surface and interlocked with said roughened surface by casting thereon in situ.

6. A roadway having a narrow, band-like, pitted surface formed thereon, and a narrow cast metallic strip coextensive with said band-like surface, said metallic strip being of generally 35 crescent cross-section and having its two faces of inherently rough form, the rough under face of said strip being of a form complementary to 40 the contiguous band-like surface of the roadway proper and interlocked therewith by casting of the strip in situ directly thereon.

7. A roadway having a roughened, narrow, band-like, pitted surface formed thereon, and a thin metallic strip coextensive with said band-like surface, said metallic strip being formed 45 thereon by direct casting and having its under surface provided with minute bosses complementary to and interlocked with the pits of said band-like 50 roadway surface.

8. A roadway having a superficial trough formed therein, the walls of which trough are provided with a myriad of minute pits and protuberances, and a thin metallic inlay of a thickness greater 55 than said trough, said inlay being formed therein in situ and having its under face in direct contact with said trough walls and of a roughened configuration complementary to and interlocked with said trough walls.

9. A roadway having a roughened, narrow, band-like surface formed therein, and a thin strip of zinc cast directly upon said band-like surface complementary thereto and mechanically 60 interlocked therewith.

10. A roadway having a roughened, narrow, band-like surface formed therein, and a thin strip of aluminum cast directly upon said band-like surface complementary thereto and mechanically 65 interlocked therewith.

11. A roadway having a roughened, narrow-band-like surface formed therein, and a thin strip of corrosion-resistant metal cast directly upon said band-like surface complementary thereto, having its under face mechanically in- 70

75

terlocked therewith, and having its exposed surface of roughened, light-diffusing character.

12. A roadway having a roughened, narrow, band-like surface formed therein, and a thin strip of corrosion-resistant metal cast directly upon said band-like surface complementary thereto, having its under face mechanically interlocked therewith, and having its exposed surface irregularly striated to afford a non-glaring traction surface.

13. A roadway having a roughened, narrow, band-like surface formed therein, and a thin strip of corrosion-resistant metal cast directly upon said band-like surface complementary thereto, having its under face mechanically interlocked therewith, and having its exposed surface diagonally striated to afford a non-glaring traction surface.

14. A crowned roadway having a narrow, pitted, band-like surface formed therein, and a thin strip of corrosion-resistant metal cast directly upon said band-like surface complementary thereto, having its under face mechanically interlocked therewith, and having its upper face laterally curved on a radius shorter than the radius of lateral curvature of the road proper.

said differential curvature being such as to divergently reflect light beams projected axially of the roadway and insure continuity of the strip even though narrowed by long, continued wear.

15. The method of defining a traffic lane upon the surface of a highway which consists in removing traffic film from said surface along the boundary of the lane, roughening said surface along said boundary to provide a myriad of minute pits and projections therein, and so casting a strip of non-corrosive metal in situ upon said clean, roughened surface as to effect mechanical interlocking of said strip upon said boundary surface.

16. The method of defining a traffic lane upon the surface of a highway which consists in removing traffic film from said surface along the boundary of the lane, roughening said surface along said boundary to provide a myriad of pits and projections therein, so casting a strip of non-corrosive metal in situ upon said clean, roughened surface as to effect mechanical interlocking of said strip upon said boundary surface, and finally diagonally striating the exposed surface of said strip.

DONALD D. TAYLOR.
